CUFF LINK

Olof V. Anderson, North Kingston, R.I., assignor to Anson, Inc., Providence, R.I., a corporation of Rhode Island

Filed Feb. 17, 1958, Ser. No. 715,632

4 Claims. (Cl. 24—97)

This invention relates to a cuff link and more particularly to the yoke of a swiveling head cuff link in which a new ornamental design is achieved, a new fastening means for the swiveling head and a new lay of the cuff link in the cuff is provided.

Cuff links in which the heads are movable to facilitate passage through the button holes of cuffs usually require some sort of pivoting or swiveling action in which a spring may be positioned for holding the head in desired position in relation to the yoke. The spring or springs usually being separately placed within the head and retained therein by a closure member or members.

One of the objects of the present invention is to simplify the construction of the cuff link in improving the yoke to achieve distinctive ornamental results on one end of the yoke and a novel construction on the other end of the yoke for coaction with the springs of the swiveling head.

Another object of the present invention is to generally improve cuff links by providing a construction which shall comprise few and simple parts that are easily assembled; cheap to manufacture and particularly adapted to quantity production, including a new ornamental result and a new two-way spring detent swiveling yoke assembly, efficient and practical to a high degree in use.

And still another object of the present invention is to provide a new cuff link which engages the button hole of the cuff in a manner to provide a new lay of the cuff link in the button hole of the shirt cuff.

And still another object of the present invention is to construct a cuff link which will readily be insertable through the usual button holes in the cuff ends, and which will not fall out of one cuff end when the other cuff end is detached. The present yoke construction provides means for retaining the cuff link in one cuff end and is so arranged as not to interfere with the insertion and removal of the cuff link from the cuff ends. This new yoke construction also holds the two cuff ends in a predetermined relationship.

Other objects of the present invention will become apparent in part and be pointed out in part in the following specification and claims.

Similar characters of reference refer to like parts in the accompanying drawings, in which:

Figure 1 is a fragmentary view of the sleeve of a shirt showing a shirt cuff and a cuff link constructed in accordance with the present invention creating a new illusion of a cuff link ornament floating on a cuff.

Figure 2 is a side elevational view of the new and improved cuff link showing a fragmentary section of a shirt cuff in cross section.

Figure 3 is a front elevational view of Figure 2 eliminating the fragmentary section of the shirt cuff.

Figure 4 is a plan view of Figure 3.

Figure 5 is a vertical cross sectional view taken along line 5—5 of Figure 4.

Figure 6 is a longitudinal detail cross sectional view of the swiveling head.

2

Figure 7 is a detail side elevational view of a modified form of yoke member.

Figure 8 is a side elevational view of a modified form of yoke member.

Figure 9 is a side elevational view of Figure 8.

Figure 10 is a vertical sectional view taken along line 10—10 of Figure 8.

Figure 11 is an enlarged perspective detail view of the pin illustrated in Figures 8, 9, 10 and 12.

Figure 12 is a view similar to Figure 5 showing a modified form of yoke end employing the pin illustrated in Figure 11.

Referring to the drawings, and particularly to Figures 2 and 5, there is illustrated a new and improved yoke

member, generally indicated by reference numeral 10. Yoke member 10 may be a stamping formed by the well known punch and die method and consists of a transverse bar member 13 rounded on each end to provide shoulders 14, 15 which terminate in two spaced apart

arms 11, 12. Arms 11, 12 are angularly positioned or offset at an angle to transverse bar 13. Arms 11 and 12 are then formed or bent into parallel relation, as at 11C and 12C. The ends of arms 11C and 12C are formed or bent at right angles on their ends to form sections

11D and 12D. The ends of sections 11D and 12D are provided with an interlocking arrangement such as a tongue and groove. The tongue consists of a major bevel 22 and a minor bevel 23. The groove consists of an interfitting major bevel 24 and a minor bevel 25. See

Figure 7. The tongue and groove provide a permanent support in the form of a square pin section of a detent when arms 11C and 12C are squeezed together in a semi-permanent set.

Transverse bar 13 is provided with a plurality of prongs

35 illustrated for example as constituting three in number 16, 17, 18. Each prong is provided with a separate ornament such as a half round bar 16A, 17A, 18A in cross section and which may be tapered toward its opposite ends, as illustrated in Figure 3. In place of ornamental bars 16A, 17A, and 18A prongs 16, 17 and 18

40 may support two bowling pins and a bowling ball or a golf club head, golf ball and golf tee or the head of a bird dog, a bird and a shot gun shell; by way of example. These ornaments will appear on a shirt cuff in the illusion 45 of being attached to the cloth of the shirt cuff. This illusionary effect is novel in jewelry which heretofore utilized one ornament because multiple ornaments were unsightly.

Referring to Figure 2 wherein is illustrated the front section 40 and the rear section 41 of a French cuff on

50 a shirt sleeve 42. Front and rear sections 40 and 41 are provided with the conventional cuff button holes 43 and 44. Dimension A the distance across shoulders 14, 15 is slightly greater than the length of button holes 43, 44.

Dimension B, see Figure 5, is equal to the thickness of a shirt cuff and will vary in accommodating a French cuff or a barrel cuff. Transverse bar member 13 lies parallel

55 to front cuff 40 as illustrated in Figure 2. Sections 11C and 12C are perpendicular to back cuff 41. Arm 12 lies in a plane to abut back cuff 41 and in co-operation

60 with head 20 holds back cuff 41 in a predetermined position so as to provide and hold front cuff 40 and back cuff 41 in pre-selected relationship; dimension "V."

The distance between the side of arm 12 which abuts the shirt cuff 41 and the side of head 20 which abuts

65 the shirt cuff 41 is substantially equal to the thickness of the shirt cuff. Thus the ends 40A and 40B of the shirt cuff are held closely together in a neat appearing relationship.

The width of the ornaments is preferably slightly

70 greater than the length of the shirt cuff button hole, so

that, cuff link 10 is centered through button hole 43.

Cuff link 10 cannot fall out of cuff button hole 43

because both the ornament and the distance across the shoulders 14, 15 is greater than the length of the button hole.

Referring to Figures 7, 8, 9 and 10 wherein is illustrated a modified form of yoke member, generally indicated by reference character 10A and consisting of a multiple prong 16B, 17B, 18B transverse bar member 13A rounded on each end to provide shoulders 14A, 15A which terminate in two spaced apart arms 11A, 12A. Arms 11A, 12A are angularly positioned or off set at an angle to transverse bar 13A. Arms 11A, 12A are then formed or bent into parallel relation as at sections 11B, 12B to form a lyre shape yoke member 10A. The ends of section 11B, 12B may be provided with a tongue and groove detent bar as previously described or sections 11B, 12B may be provided with straight ends to hold the conventional pin illustrated in Figure 11 as will presently appear.

The head 20 illustrated in Figures 2, 4 and 9 may be fixed at right angles to yokes 10 or 10A or any standard form of cam and spring arrangement may be utilized for releasably retaining the head in selected position and thereby provide a movable or swivelable or detent type head as illustrated in Figures 5, 6, 8 and 10. No claim per se is made to the construction of the swiveling head illustrated in Figures 6 and 10. Any detent head will serve the same function to yoke members 10, 10A.

Referring to Figures 6 and 10 wherein is shown in cross section a construction of a swivelling head consisting of a hollow tubular open ended shell 31 provided with a transverse orifice 32 which accommodates a square pin 36 having rounded opposite ends 37, 38. A U-shaped spring 33 is housed in shell 31 and is held in position by means of its enlarged head 34 and enlarged ends 35, 35A. A plug 39 ornamenteally closes the open end of shell 31 and is fixed therein in any well known manner such as welding or crimping as illustrated.

In the form of end illustrated in yoke 10A and which may be provided in yoke 10, sections 11B, 12B are parallel. Pin 36 by means of ends 37, 38 is permanently and rigidly secured in sections 11B, 12B with the square area 36 interposed between the U of spring 33 to provide a detent action.

In the form of end illustrated in Figures 5 and 7 and for yoke 10 and which may be provided in yoke 10A, Figures 8, 9 and 10, the right angled bent ends of arms 11B, 12B are placed between the U of spring 33. Arms 11B, 12B are then squeezed to interlock tongue 22, 23 in groove 24, 25 to provide a square area and detent for head 20. This tongue and groove construction is deemed an advantage and forms part of the new yoke concept.

Arm 12A in modified form Figures 7, 8, 9 and 10 serves the same function in holding back cuff 41 in pre-selected position when co-operating with head 20 as does arm 12 in the form illustrated in Figures 2, 3, 4 and 5. Yoke 10 may be termed a modified form of lyre shape when compared to yoke 10A.

Having shown and described preferred embodiments of the present invention, by way of example, but realizing that structural changes can be made and other examples given without departing from either the spirit or scope of this invention, what I claim is:

1. A cuff link comprising a yoke member having a transverse bar member, two spaced apart arms, rounded shoulders connecting opposite ends of said transverse bar member with said two spaced apart arms, a plurality of prongs projecting from said transverse bar member, individual ornamental members attached separately to said plurality of prongs, said ornamental members being 70

adapted to lay on the face of a front cuff end, the prongs being of a height at least equal to the thickness of the material in a normal cuff, said transverse bar member and said shoulders being greater in length than the width of the combined ornamental members, and a head mounted between said spaced apart arms.

2. A cuff link comprising a yoke member having a transverse bar member, two spaced apart arms, rounded shoulders connecting opposite ends of said transverse bar member with said two spaced apart arms, a plurality of prongs projecting from said transverse bar member, individual ornamental members attached separately to said plurality of prongs, said ornamental members being adapted to lay on the face of a front cuff end, the prongs being of a height at least equal to the thickness of the material in a normal cuff, said transverse bar member and said shoulders being greater in length than the combined width of said prongs and said ornamental member, and a head mounted between said spaced apart arms, 10

said spaced apart arms being formed at an angle to said transverse bar member so as to cause said front cuff end to lie at a predetermined angle in relation to a rear cuff end, with the rear cuff end interposed between said head and spaced apart arms at an angle complementary

15 to the angle at which said spaced apart arms are formed in relation to said transverse bar member.

3. A cuff link comprising a yoke member having a transverse bar member, two spaced apart arms, rounded shoulders connecting opposite ends of said transverse bar member with said two spaced apart arms to form a lyre shape, said transverse bar member having an angular relation to said two spaced apart arms, said spaced apart arms extending into sections parallel to each other, said parallel sections having two opposite ends one on each spaced apart arm bent at ninety degrees inwardly toward each other, a tongue formed with a major bevel and a minor bevel in one of said opposite ends, the other of said opposite ends having a groove therein, said groove being formed with a complementary major and minor bevel, means to attach an ornament to said transverse bar member and a detent head pivotally mounted and held between said parallel sections by means of said tongue and groove.

4. A cuff link comprising a yoke member having a transverse member, two spaced arms, rounded shoulders connecting opposite ends of said transverse member with said two spaced arms to form a lyre shaped yoke member, a plurality of prongs projecting from said transverse member, an ornamental member fixed to each prong, the combined length of said transverse member and rounded shoulders being greater than the combined width of said prongs and said ornamental members, the ornamental members being that portion of the cuff link remaining outside of a cuff, said prongs projecting from said transverse member a distance at least equal to the thickness of the material on one side of a normal cuff, and a swiveling head pivotally mounted between the spaced arms.
